UNITED STATES PATENT OFFICE.

JOHN A. HILLIKER, OF EVANSTON, ILLINOIS.

FRUIT-CASE.

973,429.

Specification of Letters Patent. Patented Oct. 18, 1910.

Application filed January 20, 1910. Serial No. 539,693.

To all whom it may concern:

Be it known that I, JOHN A. HILLIKER, a citizen of the United States, residing at Evanston, in the county of Cook and State of Illinois, have invented certain new and useful Improvements in Fruit-Cases, of which the following is a specification.

This invention embodies certain novel improvements in that type of cases or carriers shown and described in my Letters Patent, No. 937805, patented Oct. 26, 1909, and designed especially for use in the transportation of fruit, or the like.

The objects in the provision of the several improvements hereinafter more fully described are to accomplish a saving of material in the manufacture of the case or carrier, afford much greater facility in putting together the various parts of the case preparatory to placing the articles to be shipped therein, and to secure a construction which possesses advantages of especial merit over my previous carrier in respect particularly to the yielding or cushioning manner in which the fruit is retained within the cells or pockets provided by the construction.

A further aim of the present invention is to reduce the amount of folding necessary in order to set up or assemble the several parts of the fruit case by the elimination of certain folds provided in my patented construction, and the substitution therefor of other means for accomplishing the purpose thereof in a more simple, substantial, and conveniently operable manner as will be pointed out fully as the description proceeds.

In the accompanying drawings Figure 1 is a perspective view of a case, carrier, or tray made in accordance with the present invention; Fig. 2 is a plan view of the blank from which the body of the case is formed; Fig. 3 is a plan view of the blank which is folded to form the longitudinal partitions; Fig. 4 is a view similar to Fig. 3 of the blank that when folded constitutes a transverse partition; Fig. 5 is a fragmentary view showing a corner portion of the carrier and illustrating more clearly the manner in which such portion is formed; Fig. 6 is a fragmentary perspective view showing an end portion of one of the transverse partitions; Fig. 7 is a transverse sectional view through the carrier; Fig. 8 is a longitudinal sectional view through the carrier, articles of fruit being illustrated in dotted lines in

position in certain cells or pockets, and the yielding of the walls of the partitions being shown by dotted lines; Fig. 9 is a fragmentary top plan view, partly broken away and shown in section, bringing out clearly the 60 interlocking portions of a corner of the carrier and illustrating the manner of spacing the walls of the ends and sides thereof.

Throughout the following detail description and on the several figures of the drawings similar parts are referred to by like reference characters.

In general construction the fruit carrier hereinafter described is quite similar to my patented invention before referred to in that the improved construction embodies the provision of a shallow receptacle, tray, or case, composed of a bottom 1, sides 2, and ends 3. There is received in the receptacle aforesaid a filler or series of longitudinal and 75 transverse partitions 4 and 5 respectively, the said partitions as well as the sides and ends of the receptacle being of double-walled structure. At opposite central points in the sides 2 are provided finger openings 80 6 to facilitate lifting the receptacle in handling the fruit, it being contemplated that each of the receptacles or carriers constituting the present invention shall be placed with others in a box or large case, disposed one upon the other and transported in such condition. The bottom 1 may be provided with any suitable number of openings 7 for the purpose of ventilation. The body of the receptacle or carrier is preferably made from a single blank of material such as straw-board, chip-board, or the like, the blank being folded at its edges to provide the inner and outer walls of the sides 2 and ends 3. In like manner the several 90 partitions 4 and 5 consist of folded material such as used for making the body of the receptacle, and the folding providing spaced walls for said partitions. As shown the longitudinal partitions 4 are provided with 100 notches 4' at their lower edges and the central portions of said notches have tongues 4'' projecting downwardly therefrom, said tongues being adapted to enter the space between the walls of the partitions 5 and constituting spacing members near the lower edges of said walls which permit, however, the yielding of the walls under pressure caused by placing fruit in the cells of the receptacle. The partitions 5 are formed 110

- with slots 5' leading from their upper edges and terminating a short distance above their lower edges, said lower terminals of the slots having upwardly projecting tongues 5" which engage between the walls of the partitions 4 and constitute spacing members between said walls, performing practically the same function with respect thereto, as is performed by the tongues 4" in respect to 10 the partitions 5. It is especially advantageous that the spacing means for the walls of the partitions 4 and 5 as well as for the walls of the sides and ends of the receptacle, be adjacent to the lower edge portions of 15 said parts because the most flexibility of the walls is required at points about midway between their lower and upper edges, or where the articles of fruit when in the cells have their largest diameter, ordinarily speaking. 20 The above is illustrated very clearly in Fig. 7 of the drawing.
- At their ends the partitions 4 are formed with the auxiliary tongues 4^a the width of which is one-half that of the tongues 4", 25 said tongues 4^a passing through openings 3' in the inner walls of the ends of the receptacle and thus engaging between the two walls of such ends forming spacing members therebetween, the end portions of the 30 walls of said partitions 4 being in turn held separated by tongues 3" acting in a manner similar to the action of the tongues 5" of the partitions 5. In a similar way the transverse partitions 5 have the tongues 5" 35 at their extremities which engage in openings 2' of the inner walls of the sides 2, said walls of the partitions 5 at the extremities being spaced by the tongues 2" which coact similar to the tongues 5".
- 40 In view of the foregoing it will be apparent that the partitions forming the cells in the present form of fruit receptacle coact with the sides and ends to hold the walls of the latter spaced, but yieldable to afford the 45 desired advantages. The walls of the sides and ends, however, are held spaced by means other than that above set forth, and referring particularly in this connection to Fig. 5 it will be observed that a peculiar corner 50 folding is provided. The outer wall of the end 3 is formed with an end extension 8, and the inner wall of the side 2 overlaps said extension 8 and itself is formed with a locking tongue 9 which engages with a slit 10 in 55 the end 3. After the tongue 9 has been interlocked with the end 3 the inner wall of the end is folded over the tongue and said inner wall has a projection 11 at its extremity adapted to be received in a slit 12 at the 60 point where the tongue 9 bends from the side 2. By the tongue 9 the walls of the side 2 are held in spaced rotation at the extremities. In other words the manner of connecting the sides and ends of the receptacle

at the corners is especially advantageous in 65 that the connecting means increases the flexibility of the inner walls, or in other words provides the flexibility most desirable to firmly hold the fruit in place and yet not in any way damage or injure the fruit by contact or pressure with respect thereto. 70

Having thus described the invention, what is claimed as new is:

1. A fruit carrier comprising sides and ends composed of integral double walls, and 75 a filler within said carrier so connected with the sides and ends as to hold the walls of the latter in spaced relation.

2. A fruit carrier comprising sides and ends composed of integral double walls, partitions separating the carrier into cells or pockets, and means connecting the partitions with the sides and ends in such a manner as to hold the inner walls of the sides and ends in yielding spaced relation to the outer 85 walls.

3. A fruit carrier comprising sides and ends composed of double walls, partitions separating the carrier into a plurality of cells or pockets, each partition being composed of 90 double walls, means carried by the partitions for holding the walls of the sides and ends in spaced relation, and means carried by the sides and ends for holding the walls of the partitions in spaced relation. 95

4. A carrier for fruit comprising sides and ends composed of double walls, a connection between the sides and the ends for holding the same in operative positions, said connection also constituting positive means 100 for holding the walls of each side and end spaced.

5. A fruit carrier comprising sides and ends, each composed of double walls, interlocking means between the sides and ends 105 for holding them in operative positions, said interlocking means also holding the walls of each side and end in spaced relation.

6. A fruit carrier comprising sides and ends, each side and end consisting of double 110 walls, a tongue carried by one side and having interlocking connection with a wall of the end to hold the double walls of the side in spaced relation.

7. A fruit carrier comprising sides and 115 ends each composed of double walls, the inner wall of a side being provided at an end thereof with a tongue-interlocking with the outer wall of the adjacent end to hold the sides and ends in operative position and 120 at the same time positively holding the walls of each side and end spaced.

8. A fruit holding carrier comprising sides and ends composed of integral double walls, means at the corners of the carrier for holding the walls spaced at the corner portions, and a plurality of crossed partitions 125 in the carrier interlocking with the inner

walls of the sides and ends at intermediate points, the interlocking means coacting to hold the walls in spaced relation.

9. A fruit holding carrier comprising a bottom, the edge portion of which is folded upwardly and thence downwardly to provide integral sides and ends composed of double walls, and a filler within the carrier

so interlocking with the sides and ends as to hold the walls thereof yieldably apart. 10

In testimony whereof I affix my signature in presence of two witnesses.

JOHN A. HILLIKER.
